George R. McRennott
By P. Anthony Vinay

UNITED STATES PATENT OFFICE.

GEORGE R. McDERMOTT, OF CHICAGO, ILLINOIS.

LADLE-DRYING APPARATUS.

Application filed August 25, 1920. Serial No. 405,984.

To all whom it may concern:

Be it known that I, GEORGE R. McDERMOTT, a citizen of the United States, residing at Chicago, in the county of Cook and State of Illinois, have invented certain new and useful Improvements in a Ladle-Drying Apparatus, of which the following is a specification.

My invention relates to apparatus for use in drying ladles and has for its particular object the provision of ladle drying apparatus in which a flame can be introduced into a ladle so that the ladle is quickly dried and all moisture removed therefrom.

In blast furnace operation it is essential that all receptacles in which molten steel is poured should have all the moisture removed therefrom, as disastrous results have followed the pouring of molten steel or iron into receptacles in which there is a small quantity of water, or where there is any moisture in the ladle or the lining of the ladle.

Another and further object of my invention is the provision of a drying apparatus comprising a burner centrally located of a cover of substantially the same diameter of the inside of the vessel, as for instance a ladle, or slightly greater than the diameter of the vessel so that as the cover is placed over the vessel, but separated therefrom, a slight distance, a flame directed downward from the burner towards the bottom of the vessel will turn outward and upward along the inside side walls of the vessel and pass outward over the top edge of the vessel and under the cover thus thoroughly drying the walls of the vessel.

Another object of my invention is the provision of means whereby oil may be mixed with air and burned directly inside of the ladle, so that all of the moisture is removed therefrom prior to the pouring of steel into the ladle, or the device may be used for the drying of molds prior to the pouring of steel therein.

Another and further object of my invention is the provision of ladle drying apparatus which is simple in operation and efficient in results, and which secures a maximum result with a minimum use of fuel.

These and other objects of my invention

will be more fully and better understood by reference to the accompanying sheets of drawings, in which—

Figure 1 is a side view in elevation showing the ladle drying apparatus and a ladle in position to be placed upon the ladle holding stand and a section of the platform upon which the apparatus is mounted; and

Figure 2 is a detail sectional view of the burner and portion of the ladle cover.

Referring specifically to the drawings, 10 and 11 are foundations upon which vertically extending arms 12 and 13 respectively, are secured and which are adapted to support a ladle 14 by engagement with the trunnions 15 and 16 on each side of the ladle 14 and which rest in seats 12^a and 13^a in the upper ends of the arms 12 and 13. A vertically extending beam 16^b is provided which sets upon the foundation 10 and supports a transversely extending beam 17 which is secured to the member 16^b at one of its ends and is supported at its opposite end by a foundation and a beam similar to the foundations 10 and 16^b. A pair of horizontally extending beams 16^a are provided which are secured to the beam 17 and which with the beam 17 forms the foundation for a platform 17^a upon which the operator stands. Mounted upon the beam 17 is a crane 18 secured to the beam 17 in any approved manner, and having a socket 19 into which a vertically extending hollow standard 20 is fitted. Secured to the upper end of the standard 20 in any approved manner, as by the strap 21, is a horizontally extending arm 22. An arm 23 extending parallel with the standard 20 is provided, secured at its upper end to the member 22 and at its lower end to members 24 which engage the standard 20 on each of its sides. Secured to the members 24 is also an upwardly extending arm 25 which is secured to the member 22 at about its middle portion and forms a support for the member 22, the standard 20, and members 22, 23 and 25 forming a crane by means of which the ladle cover and burner herein-after described are suspended and moved into position over a ladle.

A drum 26 is provided which is mounted upon the members 24 and is operated by a crank 27 and has a cable 28 wound thereon which extends over a

pulley 29 secured to the member 22 near its inner end and passes outwardly along the arm 22 over a pulley 30, secured to the member 22 near its outer end and thence downward, and has a hook 31 at its lower end. A ladle cover 32 is provided which has upwardly portions 33, 33 by means of which cables 34, leading to the hook 31 are provided so that the ladle cover is held suspended and is under the control of the operator by means of the cable 28 wound around the drum 26.

An air supply pipe 35 is provided leading to any suitable source of compressed air, the said pipe 35 being connected to the hollow standard 20 by means of an elbow 36. A cap 37 is provided for the hollow standard 20 having a ball joint 38 secured thereto and to which a pipe 39 is secured in any suitable manner, the said pipe 39 leading outward parallel with the member 22 and is secured to the outer end thereof by means of a clip 40. A flexible pipe or hose 41 is secured to the pipe 39 by means of a suitable connection 42^a and through which compressed air is supplied to the burner as hereinafter described. An oil supply pipe 42 is provided which passes upward along the arm 25 to the member 22 and thence downward and has secured thereto a flexible hose or pipe 43 by means of a suitable connection 44. Mounted within an opening 45 in the ladle cover is a burner 46, the said burner being secured to the ladle cover by means of angles 47 and 48 in any approved manner. The burner comprises a cylindrical member 47^a having an opening 48^a therein and a cap 49 which is secured in position by means of bolts 50, 50. A nozzle 51 which extends into the opening 48^a of the burner is provided, the nozzle 51 being in threaded engagement with the cap 49 and thereby held in position. Openings 52, 52 are provided in the side walls of the member 49 and through which atmospheric air is taken into the combustion chamber 48^a. A globe valve 53, to which the air supply pipe 41 and oil supply pipe 43 are connected, is provided to which is also connected the nozzle 51 by means of a connection 54. A valve stem 55 having a seat on its lower end in the usual form is provided and having a wheel 56 which provides means for shutting off the supply of oil and air, as will be hereinafter described.

In the operation of the device the ladle 14 is placed in position by means of a crane upon the ladle supports 12 and 13 and the crane carrying the ladle cover is swung upward so that the ladle cover is immediately over the ladle. The valve 53 is open so that the compressed air is admitted into the nozzle 51 carrying with it a supply of oil through the pipe 43, the mixture being lighted and the ladle cover is thereupon

swung into position over the ladle and lowered to within about one-half inch of the top of the ladle. The globe valve 53 is thereupon opened wider and the flame is directed downwardly into the ladle 14, is deflected by the bottom of the ladle and passes outwardly and upwardly along the sides of the ladle and out between the cover 32 and the upper edge of the ladle so that the ladle is completely dried out, the cover 32 being allowed to remain out of contact with the upper edge of the ladle 14 so that the flame, smoke, steam and products of combustion can escape from the ladle. A further supply of air is pulled inwardly through the openings 52 and the cap 49 so that the oil is thoroughly mixed with the air and proper combustion of the oil is secured. The apparatus is allowed to remain in position until the mold is thoroughly dried, whereupon the ladle cover is swung out of position and the mold is ready to be removed to receive a charge of molten metal.

It will be understood that the crane is centrally located between four ladle stands so that each crane can be used alternately for swinging the ladle cover and burner into position over each ladle stand.

While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention, and also in the use of the apparatus for the drying of molds or any other closed receptacle, or the lining of such receptacle.

I claim:

1. In a ladle drying apparatus, the combination of a burner, means for supplying fuel to said burner, a cover through which said burner extends and means for suspending the cover above a ladle, the marginal edges of the said cover conforming in shape substantially to the form of the opening in said ladle, the said cover plate being held out of contact with the ladle during the operation of the burner.

2. In a ladle drying apparatus, the combination of a burner, means for supplying a fuel to said burner, a cover through which said burner extends of slightly larger diameter than the opening of said ladle and conforming in shape thereto and means for suspending the cover of a ladle and out of contact with the upper marginal edges thereof.

3. In a ladle drying apparatus, the combination of a burner, means for supplying liquid fuel and air to said burner, a cover through which the said burner extends, and means for suspending the cover over a vessel, the said cover being slightly larger in

diameter than the inside diameter of the vessel, and being held out of engagement with the ladle during operation of the said burner.

5. 4. In combination, a revolving crane, a cover plate suspended from said crane, a burner in said cover plate and extending

therethrough, means for supplying fuel to said burner and means carried by said crane whereby the said cover is held over a vessel and out of contact therewith. 10

Signed at Chicago, Illinois, this 11th day of August, 1920.

GEORGE R. McDERMOTT.
